YARN CARRIER SELECTOR MECHANISM
FOR KNITTING MACHINESPaul Krenkel, Philadelphia, Pa., assignor to
Textile Machine Works, Reading, Pa.

Application December 5, 1932, Serial No. 645,664

39 Claims. (Cl. 66—127)

My invention is a yarn carrier selector mechanism for knitting machines, and particularly for full-fashioned silk hosiery knitting machines of the "Cotton" type, and my improvements are particularly designed to facilitate the manufacture of "ringless" silk hosiery in which at least three successive courses of loops are formed from yarn drawn from different sources.

The type of full-fashioned silk hosiery knitting machine to which my improvements are particularly applicable is characterized by a bank of en masse movable knitting needles along which yarn is laid and between which the yarn is kinked. The yarn for each course is laid by one of a series of carriers mounted on a series of carrier rods and operable selectively through a friction box and friction rod reciprocated rectilinearly by a Coulier mechanism, which concurrently reciprocates rectilinearly a slur bar (sometimes called a flight bar) having a slur cock for sequentially advancing sinkers for kinking the yarn between the needles. Suitable stops limit the rectilinear travel of the carrier rods before the end of the throw of the friction rod and slur bar by the Coulier mechanism, and during this overthrow the friction rod slides through the friction box against the friction thereof.

By my improvements, the friction box may be automatically connected with a different carrier rod at the end of each rectilinear movement so that a yarn from one source of supply may be laid along the needles on the movement of the friction rod in one direction, a yarn from a second source of supply may be laid along the needles on the movement of the friction rod in the opposite direction, a yarn from the third source of supply may be laid along the needles on the movement of the friction rod in the original direction, a yarn from the first source of supply may be laid along the needles on the second movement of the friction rod in the reverse direction, and so on, without any "idle" courses or "drawbacks."

The connection of the friction box with the respective carrier rods is effected through selector mechanism supported, and traversed longitudinally of the machine, by the friction box.

Actuation of the selector mechanism to effect selection of the carrier rods is preferably effected, after each throw or traverse of the friction box is completed, through rotary cam mechanism supported adjacent to the slur, and friction rods but independently of the friction box, and motion is transmitted, through such cam mechanism from the main shaft of the machine to the

selector mechanism through positively acting parts and without the intervention of a pattern chain.

Such positively acting parts preferably include the usual Coulier mechanism and slur bar and in addition thereto comprise wedge-like cams on the slur bar, pawl and ratchet mechanism, a rotatable cam shaft having the rotary selector cams thereon, and lever, link and spline mechanisms connecting the selector cams and selectors. The wedge-like cams are so spaced that only one thereof engages and actuates the pawl and ratchet mechanism on each throw of the slur bar to rotate step by step the rotatable cam shaft which has its axis parallel to the axis on which the selector mechanism turns, rotates or arcuately oscillates.

Such shaft is mounted in stationary bearings and lies adjacent to the slur bar which, together with the friction rod, moves rectilinearly with respect to the shaft throughout the throw of the slur bar and friction rod. The friction box, together with the selector mechanism thereon, is moved by the friction rod rectilinearly with respect to the selector cams, cam shaft and pawl and ratchet mechanism during the laying of the yarn, and stands stationary with respect thereto during the overthrow of the friction rod and the actuation of the selectors.

My improvements further provide for holding or biasing a plurality of carrier rods against their end stops while a selector is moved by the mechanism above described into position for engaging one of the held rods to traverse it across the machine on the next throw of the friction rod. Such holding and biasing is preferably effected by a second selector, which remains stationary, and holds the friction box stationary, during the friction rod overthrow and the movement of the first-named selector into engaging position by the slur bar through the rectilinearly stationary cam shaft.

When the first-named selector has moved the selected carrier rod to the opposite end of the machine against its end stop, such selector remains stationary and holds the rod it has just moved and another carrier rod against their end stops, and also, while still stationary, such selector holds the friction box stationary throughout the friction rod overthrow and while the second-named selector is moved, into position to engage a held rod, by the action of a slur bar cam through the rectilinearly stationary cam shaft and other mechanism above described during the overthrow of the friction rod. By eliminating any move-

ment of the first named selector in a plane transverse to the carrier rods during the friction rod overthrow there is avoided any possibility of rectilinear movement of the friction box during 5 the friction-rod-overthrow, such as may occur when the selector engaging a rod is moved transversely thereto during an overthrow movement of the friction rod.

Each selector has a notched edge movable 10 transversely to the carrier rods and forming tongues so spaced as to permit the engagement of a selector with a boss on any one of a plurality of carrier rods or to permit the boss on any one of the carrier rods to pass through a notch aforesaid upon the movement of the selector rectilinearly along the carrier rods.

The selectors preferably have splined connections with a pair of concentric shafts mounted on the friction box so that they may be independently turned, rotated or oscillated through an arcuate movement on an axis parallel with the axis of the selector cam shaft through links and levers rocked by the selector cams on the cam shaft.

25 The characteristic features and advantages of my improvements will further appear from the following description and the accompanying drawings in illustration thereof:

In the drawings, Fig. 1 is a fragmentary perspective view of a portion of the knitting head of a full-fashioned knitting machine illustrating diagrammatically the knitting of a portion of a fabric from yarns laid from three sources in sequence by the mechanism of my invention; Fig. 2 is a transverse sectional view of a conventional knitting machine equipped with my carrier rod selecting attachment; Fig. 3 is an enlarged transverse sectional view taken substantially on the lines 3—3 of Figs. 5 and 6; Fig. 4 is a fragmentary view of the selector plate complementary to the selector plate shown in Fig. 3 and indicating its position relative to the latter at the same point in the cycle of operation; Fig. 5 is a longitudinal elevation partly in section of the carrier rod selector mechanism looking from the front of the machine; Fig. 6 is an elevation of cam and lever mechanism by which the selector mechanism is operated, the view being taken from the front of the machine; Fig. 7 is a detached end view of pawl and ratchet mechanism and associated parts taken from the right hand end of Fig. 6; and Fig. 8 is an elevation of the cam mechanism shown in Fig. 6 but with the lever mechanism and other parts removed.

55 My improved attachment is shown in the drawings applied to a usual type of full-fashioned silk hosiery knitting machine having a series of thread carriers and thread carrier rods including the carriers 23, 24, and 25 and carrier rods 23a, 24a and 25a to which the carriers are respectively connected and which are mounted in the usual slotted bed 26. The carriers 23 and 25 may be considered as initially normally positioned at rest at the left hand end of the machine and the carrier 24 may be considered initially normally at rest at the right hand end of the machine. Each carrier rod has fixed thereto a stud 23b, 24b and 25b which project upwardly into the path of friction box mechanism for selectively operating the carrier rods.

70 The friction box mechanism consists of a housing 27 sleeved on the usual friction rod 28 and provided with usual friction shoes (not shown) operable by the lever 29 for clamping the friction box to the friction rod so that the

friction box is moved by the friction rod when the latter is not opposed by resistance greater than the tractive effect of the friction shoes. When the resistance to the movement of the friction box exceeds the tractive effect of the 5 friction shoes on the friction rod 28, the friction rod slides through the friction box in the usual manner, and when the lever 29 is thrown to position to loosen the friction shoes from the friction rod 28 the latter may slide freely through the 10 friction box.

An extension 27' of the friction box housing 27 has journalled therein a sleeve 30 to which is fixed a radial plate 31. A key 32 is fixed to the sleeve 30 and this key is engaged in a spline slot 15 33 in the bottom of a tube 34 journalled in bearings 35 and 36 mounted at the ends of the bed 26. A sleeve 37 is sleeved within the sleeve 30 and has fixed thereto a radial plate 38 similar to the plate 31. A key 39 is fixed to the sleeve 20 37 and is engaged in a spline slot 40 in a shaft 41 journalled in the tube 34. The upper side of the tube 34 and the lower portion of the sleeve 37 each have a segment cut therefrom to form an opening permitting limited relative rotation of 25 the shafts 41 and 34 and their attached parts. Nuts 43 and 44 are screwed onto the threaded end 37' of the sleeve 37, the face of the nut 43 engaging the face of the plate 31 so that the plates 31 and 38 may be adjusted in fixed axial 30 positions relatively to one another by drawing up the nuts.

The plate 31 is provided with the depending tongues 31a and 31b spaced by the notch 31c, and the plate 38 is similarly provided with the 35 depending tongues 38a and 38b spaced by the notch 38c.

The shafts 34 and 41 have fixed to the respective ends thereof respective arms 34a and 41a having pivotally connected therewith the respective links 45 and 46. These links are respectively connected with the levers 47 and 48 which are fulcrumed on a shaft 49 mounted in brackets 50 supported by an arm 51 attached to the frame of the machine. Links 52 and 53 connect the 45 respective levers 47 and 48 with the lever arms 54 and 55 fulcrumed on a shaft 56 fixed in the bearings 51 of the brackets 50.

The levers 47 and 54 have the double track rollers 58 and 59 pivoted thereto and engaged by 50 a complementary double track cam 60 and the levers 48 and 55 have similar double track rollers 61 and 62 pivoted thereto and engaged by a complementary double track cam 63 so that the lever motions are at all times positively controlled 55 without the need of springs.

The cams 60 and 63 are formed integrally with a sleeve 64 loosely journalled on the usual narrowing shaft 65 which passes through collars 66 of the brackets 50, and these collars prevent 60 axial movement of the cams along the narrowing shaft. A brake band 68, adjustably fixed to the bracket 51, has its friction surface seated in the groove 69 of the sleeve 64 to prevent movement of the cams by the narrowing shaft or the overthrow of the movement of the cams.

The cam 63 has fixed thereto a ratchet wheel 70 adapted to be rotated by a pawl 71 pivotally mounted on an arm 72 of the collar 73 sleeved on an extension 64' of the sleeve 64. An arm 70 74 of the collar 73 is pivotally connected with a link 75, the opposite end of which is pivotally connected with a slide or rod 76 reciprocable rectilinearly in the housing 77. The lower end of the shaft 76 has pivotally connected therewith a 75

roller 78 adapted to be engaged by cams 79 and 80 fixed adjacent to opposite ends of the usual slur cock bar 81.

In the position of the mechanism shown in the drawings, the carrier 23 is stationary at the left hand end of the machine looking from the front, the carrier 24 is stationary at the right hand end of the machine, and the carrier 25 is being moved toward the left to complete the laying of the yarn 3 to form a course of loops. In this position of the mechanism the selector plate 38 is so set that in starting from the right it has cleared the lug 24b and its flange 38b engages the lug 25b to effect the leftward movement of the carrier rod 25a and carrier 25 as a result of the leftward movement of the friction rod 28 and friction box 27. During this leftward movement the selector plate 31 is so set that its notch 31c will clear the lug 23b of the carrier rod 23a to permit the complete throw of the carrier 25.

When the friction box 27 reaches its extreme left position the tongue 38b of the selector plate 38 engages the end of the lug 23b so that the impact of the carrier rod 25a against its usual stop shall not cause the rod 23a to jump out of position. The distance between the inner faces of the plates 31 and 38 is slightly greater than the width of the lugs 23b, 24b or 25b, so that when the box 27 is in its extreme leftward position there is slight clearance between the inner-face of the selector plate 31 and the end of the lug 23b, so that the selector plate 31 may be turned, rotated or arcuately oscillated on its axis without frictional engagement with the lug 23b to such position that the notch 31c will register with and clear the lug 25b and the tongue 31b will be in position to engage the lug 23b upon the movement of the friction box toward the right of the machine.

This movement of the plate 31 so that its notch 31c is shifted from registration with the lug 23b to registration with the lug 25b is effected by the action of the cam 60 on the levers 47 and 54. The cam 60 is preferably so shaped that it effects the movement of the plate 31 only on every other upward movement of the slide 76, so that the plate 31 is moved by its cam 60 only when the friction box 27 is at the left hand end of the machine, looking from the front. Similarly the cam 63 is so positioned and shaped relatively to the cam 60 and to the plate 38 that the latter is moved only on every other upward movement of the slide 76 and when the friction box 27 is at the right hand end of the machine. Each cam 60 and 63 is so shaped that it may move its corresponding plate 31 or 38 to any one of three positions, viz., to a position in which the notch in the plate will register with the lug 23b, a position in which the notch in the plate will register with the lug 25b, and a position in which the notch in the plate is behind and will not register with any of the lugs, as for instance the position of the plate 38 in Fig. 4.

When, as above noted, the plate 31 has been moved by its cam 60 so that its notch 31c registers with the lug 25b and the plate 38 is still in the position shown in Fig. 3, the friction box 27 moves toward the right. This movement causes the tongue 31b to engage the lug 23b and move it toward the right, and when the rightward limit of movement is reached the tongue 31b engages the end of the lug 24b to prevent its jumping out of its position as a result of the impact caused by the stoppage of the rod 23a.

The plate 38 is now shifted by its cam 63 so that

its notch 38c registers with the lug 23b and its tongue 38b engages the lug 24b. The plate 31 is not shifted in this position of the friction box. The friction box then moves leftwardly and the tongue 38b carries leftwardly the lug 24b and leaves the carrier 23 at the right hand end of the machine. On the completion of this leftward movement the tongue 38a engages the end of the lug 25b so as to prevent its jumping out as a result of the impact caused by the stoppage of the rod 24a, the notch 31c having of course permitted the plate 31 to pass the lug 25b in its leftward movement.

The plate 31 is now shifted by its cam so that its notch 31c occupies its extreme rearward position and the tongue 31b engages the lug 25b. On the movement of the friction box 27 to the right, the notch 38c permits the passage of the plate 38 past the lug 23b, which however, is then engaged by the tongue 31b, to prevent the lug 23b from jumping out as a result of the impact caused by the stoppage of the rod 25a.

The plate 38 is then shifted by its cam so that its notch 38c registers with the lug 25b and its tongue 38b engages the end of the lug 23b. Upon the leftward movement of the friction box 27, the tongue 38b moves leftward the lug 23b and on the completion of the throw the tongue 38b engages the end of the lug 24b and prevents it from jumping out of its place.

At the conclusion of the leftward movement, the plate 31 is shifted by its cam so that its notch 31c registers with the lug 23b and its tongue 31b engages the lug 24b and carries it toward the right. The notch 38c permits the plate 38 to pass the lug 25b, which, however, is engaged by the tongue 31a and prevented from jumping out of position as a result of the impact due to the stoppage of the rod 24a. At the conclusion of this movement of the friction box 27 toward the right, the plate 38 is shifted by its cam so that its notch 38c is moved to its extreme rearward position and its tongue 38b engages the lug 25b, and the described cycle of operation is repeated.

My improved attachment is primarily designed for laying yarns from different sources, and each composed of continuous sections of varying thickness, one after another to permit the knitting of fabric as shown in Fig. 1.

As illustrated diagrammatically in Fig. 1, the course of loops 1a was laid on the sinkers 20 by the carrier 23 from yarn 1 drawn from the cone 1A during a movement of the carrier 23 from left to right, as hereinbefore described. The laid yarn, after being acted on by the dividers in the usual manner, was knitted by the needles 22 through the last course of the welt section A. When the course of loops 1a was completed, the carrier 23 was left at the right hand end of the machine and the carrier 24 was connected with the friction box as hereinbefore described and moved toward the left. During such movement the carrier 24 laid on the sinkers 20 a yarn 2 drawn from a second supply or cone 2A, this yarn being laid from right to left and in position to be interlaced with the course 1a by the knitting needles 22 to form the courses of loops 2a. When the course of loops 2a was completed, the carrier 25 was connected with the friction box as hereinbefore described and laid a yarn 3 from a third cone or source of supply 3A. The carrier 25 moved from left to right and placed a section of the yarn 3 on the sinkers in position to be

divided and knitted into the course 2a to form the course of loops 3a.

The carrier 23 was then moved by the friction box from right to left to lay a section of yarn 1 on the sinkers in position to be knitted by the needles 22 through the course 3a. When this yarn section had been interlaced by the needles to form the course 1b, the carrier 24 was moved by the friction box from left to right, to the position shown, to lay a further section of the yarn 2 in position on the sinkers for interlacing with the course 1b. The dividers and needles were then operated to form the course of loops 2b interlaced with the course of loops 1b. The carrier 25 was then moved from the right toward the left to lay a further section of yarn 3 in position to be knitted by the needles through the course of loops 2b as shown. Such knitting will result in the formation of a course of loops 3b and the knitting may be continued by repeatedly forming courses from the different yarns in the sequence described.

In practice, it results that any subnormal or abnormal thickness of a section of the yarn 1 is substantially compensated for by an average thickness or a complementary abnormal or subnormal thickness of the sections of the yarns 2 and 3 laid in sequence. Conversely, the variations in the thickness of different sections of the yarn 2 are compensated for by unlike variations in the yarns 1 and 3, and variations in the thicknesses of sections of the yarn 3 are compensated for by unlike variations in the thickness of adjacent sections of the yarns 1 and 2. The result is that the fabric as a whole has a uniform average sheerness free of any disfiguring bands of noticeable width of excessive or insufficient sheerness, and has a uniform average density and texture so that fabrics containing the same number of courses are of substantially the same length and shade.

Having described my invention, I claim:

1. In a knitting machine, a plurality of yarn carriers, a plurality of sources of yarn supply from which the respective carriers draw yarn, carrier rods with which the respective carriers are connected, a friction box having connected therewith a pair of selectors, each movable into position to engage or disengage each of the aforesaid carrier rods, and means for shifting the respective selectors while positioned out of operating engagement with said rods.

2. In a knitting machine, the combination with a plurality of carrier bars and stops therefor of a plurality of selectors for operating said bars in sequence, one of said selectors being positioned to check the jumping of a bar aforesaid when another bar is impacted against its stop by the movement of said selector.

3. In a knitting machine, the combination with a plurality of carrier bars and stops therefor, of a pair of selectors for operating said bars in sequence, means for positioning one of said selectors to check the jumping of one of said bars when another of said bars is impacted against its stop by the movement of said first selector, and means for positioning the second selector to check the jumping of a third carrier bar when the first named carrier bar is impacted against its stop by the movement of the second selector.

4. In a knitting machine, actuating means including a friction box for causing traverse in rotation of three or more carrier rods, stops for the rods at the ends of their traverse, and means

confining and holding each rod against its stop at each end of its active traverse, thereby preventing rebound thereof, and at the same time for confining and holding against rebound at the same end any idle rod resting there.

5. A knitting machine having at least three yarn carrier rods longitudinally shiftable leftward and rightward in their yarn laying traverse movements, and end stops limiting the left and right traverse movements of the rods, in combination with a longitudinally reciprocating friction box, and rod-engaging means carried by and traversely shiftable with said friction box; with control connections operating to vary methodically the position of said rod-engaging means to cause said rod-engaging means to engage selectively the carrier rods to thrust them leftward and rightward in rotation in successive traverses and to cause said means to hold each rod against its stop at the end of its each traversing shift to prevent rebound thereof and at the same time to cause said means to engage and hold positively against displacement at the same end of each traverse an idle carrier rod resting there.

6. In a knitting machine, actuating means including a friction box shiftable leftward and rightward for causing traverse in rotation of three or more carrier rods, stops for the several rods at each end of their traverse and complementary rod-engaging means movable traversely with said friction box and operable relatively upon the left and right shifts thereof, each of said means comprising a plurality of rod-engaging parts, one of such parts engaging and traversely shifting an active rod in each traversing operation and thereupon confining and holding the shifted rod against its stop at the end of its active traverse, and another of such parts at the end of the same traversing action engaging and holding against its stop another rod resting idly at the same end, whereby each traversed active rod and adjacent idle rod are prevented from rebound or displacement from their stopped positions.

7. In a knitting machine, actuating mechanism including a friction box for causing traverse in rotation of three or more carrier rods, stops for the rods at each end of their traverse, said actuating mechanism including means traversely movable with said friction box for confining and holding each rod against its stop at each end of its active traverse, thereby preventing rebound thereof, and for confining and holding against rebound at the same end any idle rod resting there.

8. The combination in a flat knitting machine of a plurality of longitudinally reciprocal thread carrier bars, driving dogs on said bars respectively, driving means for said bars operable parallel thereto and including rotary means provided with a plurality of dog-engaging parts and intermediate dog-clearing spaces, and means for intermittently actuating said rotary means to align predetermined parts and spaces with predetermined dogs for selectively coupling said bars to said driving means.

9. The combination in a flat knitting machine of a plurality of longitudinally reciprocal thread carrier bars, driving dogs on said bars respectively, driving means for said bars operable parallel thereto and including a pair of rotary laterally spaced elements provided with a plurality of dog-engaging lugs and intermediate dog-clearing spaces, and means for actuating said elements

intermittently for aligning predetermined lugs and spaces thereof with predetermined dogs on said bars for selectively coupling said bars to said driving means.

10. The combination in a flat knitting machine of a plurality of longitudinally reciprocal thread carrier bars, driving dogs on said bars respectively, driving means for said bars operable parallel thereto and including a pair of rotary laterally spaced elements adapted for independent rotation and each provided with a plurality of dog-engaging lugs and intermediate dog-clearing spaces, and means for actuating said elements intermittently for aligning predetermined lugs and spaces thereof with predetermined dogs on said bars for selectively coupling said bars to said driving means.

11. The combination in a flat knitting machine of a plurality of longitudinally reciprocal thread carrier bars, driving dogs on said bars respectively, driving means for said bars operable parallel thereto and including a pair of rotary laterally spaced elements adapted for independent rotation and each provided with a plurality of dog-engaging lugs and intermediate dog-clearing spaces, and means for alternately actuating said elements intermittently for aligning predetermined lugs and spaces thereof with predetermined dogs on said bars for selectively coupling said bars to said driving means.

12. The combination with a device adapted for driving a plurality of longitudinally reciprocal thread carrier bars of a flat knitting machine, of a pair of rotary elements carried by said driving device and respectively provided with a plurality of carrier bar engaging lugs and intermediate bar-clearing spaces for selectively coupling said bars to said driving device.

13. The combination with a device adapted for driving a plurality of longitudinally reciprocal thread carrier bars of a flat knitting machine, of a pair of rotary elements carried by said driving device and respectively provided with a plurality of carrier bar engaging lugs, and intermediate bar-clearing spaces, and a cam adapted for reciprocation parallel to, with, and in excess of said driving device to actuate said rotary elements for selectively coupling said bars to said driving device.

14. The combination with a device adapted for driving a plurality of longitudinally reciprocal thread carrier bars of a flat knitting machine, of a pair of rotary elements carried by said driving device and respectively provided with a plurality of bar-engaging lugs and intermediate bar-clearing spaces, means carried by said driving device for intermittently rotating said elements, and means operable independent of said driving device for actuating said element rotating means.

15. The combination with a device adapted for driving a plurality of longitudinally reciprocal thread carrier bars of a flat knitting machine, of a pair of rotary elements carried by said driving device and respectively provided with a plurality of bar-engaging lugs and intermediate bar-clearing spaces, means carried by said driving device for intermittently rotating said elements, and a cam adapted for operation parallel to, concurrently with, and in excess of said driving device for actuating said element-rotating means.

16. The combination with a device adapted for driving a plurality of longitudinally reciprocal thread carrier bars of a flat knitting machine, of a pair of rotary elements carried by said driving device and respectively provided with a plurality

of bar-engaging lugs and intermediate bar-clearing spaces, means carried by said driving device for intermittently rotating said elements, and means operable independent of said driving device for actuating said element-rotating means. 5

17. The combination in a flat knitting machine of a plurality of longitudinally reciprocal thread carrier bars, a friction box drive rod longitudinally reciprocal parallel to said carrier bars, a friction box mounted on said drive rod, a pair of 10 rotary elements carried by said friction box and respectively provided with a plurality of carrier bar engaging lugs and intermediate carrier bar clearing spaces, and ratcheting mechanism for intermittently rotating said rotary elements for 15 selectively coupling said carrier bars to said friction box.

18. The combination in a flat knitting machine of a plurality of longitudinally reciprocal thread carrier bars, a friction box drive rod and a slur 20 cock bar longitudinally reciprocal parallel to said carrier bars, a friction box mounted on said drive rod, a pair of rotary elements carried by said friction box and respectively provided with a plurality of carrier bar engaging lugs and intermediate carrier bar-clearing spaces, 25 ratcheting mechanism for intermittently rotating said rotary elements for selectively coupling said carrier bars to said friction box, and a cam carried by said slur cock bar for actuating said ratcheting 30 mechanism.

19. In a full fashioned knitting machine, the combination of a set of thread carrying bars, a pair of friction rod-operated actuators therefor, a shaft upon which said actuators are slidably 35 keyed, and flight bar operated means for rotating said shaft in step by step fashion in the operation of the machine to selectively engage said actuators with different thread carrying bars.

20. In a knitting machine, a plurality of yarn 40 carriers, a separate course of yarn supply from which each carrier lays yarn, carrier bars with which the respective carriers are connected, a plurality of selectors for operating said bars in sequence, and means for automatically shifting 45 one only of said selectors relatively to said carrier bars after a movement of a bar in one direction and shifting another only of said selectors relatively to said carrier bars after movement of a second bar in the opposite direction. 50

21. In a knitting machine, a plurality of yarn carriers, a plurality of sources of yarn supply from which the respective carriers draw yarn, carrier rods with which the respective carriers are connected, a friction box having connected therewith a pair of selectors for operating said rods, a friction bar on which said box is mounted, said bar having an overthrow beyond the maximum overthrow of said carrier rods, and means operable by a moving part of said knitting machine for automatically shifting one of said selectors relatively to said carrier rods during the overthrow of said friction bar at one end only of the machine and for automatically shifting the other of said selectors relatively to said carrier rods during the overthrow of said friction bar at the other end only of the machine. 65

22. A knitting machine comprising a plurality of yarn carriers, carrier rods with which the carriers are respectively connected, a reciprocal friction box, a pair of selectors carried by the friction box, and means for automatically operating said selectors alternately and respectively after the movement of said friction box to the opposite ends of the throw. 75

23. In combination, in a knitting machine, a set of knitting elements, first and second yarn carriers disposed in starting position at one and the same side of said set, a third yarn carrier disposed in starting position at the opposite side of said set, and means comprising a pair of selectors shiftable at different times and each having a plurality of carrier actuating tongues for operating said first and second carriers to alternately lay courses across the set in one direction and the third carrier to lay a course across the set in the opposite direction between the alternations of the first and second carriers.
24. In a knitting machine, a plurality of yarn carriers, a separate source of supply from which each carrier lays yarn, carrier bars with which the respective carriers are connected, means including a reciprocating friction-box rod for moving said bars, a pair of selectors connecting the respective bars in sequence with said friction-box rod, and means for turning one of said selectors on an axis only after each movement of the friction-box in one direction and for turning the other of said selectors on an axis only after each movement of the friction-box in the opposite direction.
25. In a knitting machine, the combination with a plurality of carrier bars and a reciprocable friction-box rod for effecting movements of said carrier bars, of means comprising selector mechanism having a member operatively connecting the friction-box rod with a carrier bar and transmitting movement to said carrier bar from the friction-box rod during movement thereof in one direction, said selector mechanism having a second member shiftable to operatively connect said friction-box rod with a second carrier bar at the end of the movement of the first carrier bar and while said first member remains stationary relative to said first carrier bar, said first member being shiftable to operatively engage a third carrier bar with said friction-box rod at the end of the movement of the second named carrier bar while said second member remains stationary relative to said second carrier bar, said second member being shiftable to operatively connect with said friction-box rod the first named carrier bar at the end of the movement of the third named carrier bar and while said first member remains stationary relative to the third carrier bar, means for shifting said selector mechanism members in the sequence set forth, and means for moving said friction-box rod between the shifts of said selector mechanism members.
26. In a knitting machine, the combination with a plurality of carrier bars of reciprocable selector mechanism comprising a pair of selectors, one of said selectors being movable to positions for engaging one or another of a plurality of carrier bars at the end of the movements of said selector mechanism in one direction only, and the other of said selectors being shiftable to positions for engaging one or another of a plurality of carrier bars at the end of the movement of said selector mechanism in the opposite direction only, and means for positioning said selectors to engage said carrier bars one after another in sequence.
27. In combination with the friction rod, friction box and slur bar of a full fashioned knitting machine, carrier rod driving means carried by said friction box, mechanism for automatically and selectively engaging and disengaging said driving means with carrier bars for the selective operation thereof, said selecting mechanism including a pair of selectors only one of which is operated by said slur bar on its throw in one direction and the other of which only is operated by said slur bar on its throw in the other direction.
28. In a full fashioned knitting machine, the combination of a plurality of yarn carriers, a friction rod and a friction box therefor, a rotatable and axially shiftable cam shaft, means comprising a pair of selectors movable with and relative to said friction box for selective operative engagement with any of said carriers, and an actuating device comprising an element bodily reciprocably shiftable longitudinally of the machine and independently of said friction box for transmitting an actuating impulse to said means to effect a selective operative engagement of one only of said selectors on the movement of said element in one direction and of the other only of said selectors on the movement of said element in the opposite direction.
29. A knitting machine comprising a plurality of yarn carriers, carrier rods with which the carriers are respectively connected, a reciprocable friction box, a pair of selectors carried by said friction box and each adapted to engage and move one of said rods and to hold said moved rod and another of said rods concurrently at the end of the movement of the first named rod and without movement of said selector relatively to said first named rod at the end of the throw thereof.
30. In a knitting machine, the combination with a plurality of yarn carriers and stops therefor, of a plurality of selectors for operating said yarn carriers in sequence, one of said selectors having a member checking the jumping of a yarn carrier aforesaid when another yarn carrier is moved to its "stop" position.
31. In a knitting machine having three or more carrier rods, stop means for the several rods at each end of their traverse, and a plurality of thrusters to cause the shifting traverse of each rod in rotation with the other rods, means for moving all the thrusters concurrently in each traversing operation, and means for selectively controlling on one traverse the position of one thruster and on the next traverse the position of another thruster as between operative and idle positions, with methodical change of control to cause the said operation of rods in rotation, each thruster after being shifted being adapted to cause the traverse of a rod, and at the end of said traverse to confine and hold the rod against said stop means.
32. In a knitting machine, the combination with a plurality of carrier bars, of two selectors for moving said bars in sequence, and means for moving each of said selectors into position for engaging a member of one of said rods while such member is biased by the other of said selectors in stationary relation thereto.
33. In combination, in a knitting machine, several yarn carriers, a corresponding number of yarn sources for several connection to the carriers, carrier rods to which the respective carriers are connected, selector mechanism for operating said rods in sequence, and comprising a pair of selectors each having a plurality of tongues movable into positions for engaging a plurality of carrier rods, the tongues of each selector being spaced to permit such selector to pass along a carrier rod without engagement therewith.

5 34. In a knitting machine, the combination with a plurality of carrier bars each having a member for engagement by a selector, of a plurality of selectors each having a plurality of spaced tongues and each movable into positions for engaging one after another the members of a plurality of bars, and means for shifting said selectors to operate said carrier bars in sequence.

10 35. In a knitting machine, the combination with a plurality of carrier bars each having a member engageable by a selector, of a plurality of selectors each having a notched edge permitting rectilineal movement of the selector relatively to a bar member, and means for shifting said selectors to move the notches therein transversely relatively to said bars.

15 36. In a knitting machine, the combination with a plurality of carrier bars each having a member for engagement by a selector, of a pair of selectors for moving said bars rectilineally in sequence, said selectors having one of said members between them during the rectilineal movement of a bar and being so spaced that when one of said members is stationary relative to one selector at the end of its rectilineal movement the other selector is movable relatively to said member free from frictional contact therewith.

20 37. A machine for knitting full-fashioned stocking webs including a series of knitting needles, a plurality of yarn carrier rods, each having means mounted thereon for feeding separate yarns to the needles, a friction box for reciprocating said yarn carrier rods so that their yarn feeding means will feed the yarns to said needles, a friction rod for operating said box and having an overthrow, and two shiftable selectors for automatically connecting said box with each of said carrier rods so that its particular yarn carrier will only feed yarn to the knitting needles during the knitting of every third course

of the stocking web, one of said selectors being stationary and holding the friction box against movement during the overthrow of said friction rod and the shift of the other of said selectors.

38. The combination, in a flat knitting machine, having means for knitting yarn into courses of loops, of a group of three longitudinally reciprocable thread carrier bars each having a driving dog thereon, driving means for said bars reciprocable parallel thereto, and selecting means including dog engaging means traversing with said driving means and also operating to and fro transversely of said bars generally parallel to the plane of said bars for changing the driving connection from one bar of said group of three to another between every two succeeding courses for selectively operating the bars of said group seriatim to effect a complete cycle of operations thereof, said selecting means also including dual cam means delivering positive thrusts some in one direction and some in the reverse direction for effecting three selective movements of a single member of said dog engaging means and for moving said single member in unilateral continuous steps of varying lengths so that said single member drives each of said bars.

39. In a flat hosiery knitting machine provided with a reciprocable friction rod, a friction box thereon, and a multiplicity of carrier rods each having means thereon adapted to be engaged by a driving member, the combination of a member pivotally mounted on said box to move transversely to the path thereof and having means adapted for driving engagement with said means on each of said carrier rods, selector cams arranged to move said pivoted member into driving engagement with said rods in predetermined sequence and means to move said cams step-wise always in the same direction.
